UNITED STATES PATENT OFFICE.

JOHN PETTERSON, OF MINGO JUNCTION, OHIO.

RATCHET-DRILL.

SPECIFICATION forming part of Letters Patent No. 678,128, dated July 9, 1901.

Application filed November 26, 1900. Serial No. 37,759. (No model.)

To all whom it may concern:

Be it known that I, JOHN PETTERSON, a citizen of the United States of America, residing at Mingo Junction, in the county of Jefferson 5 and State of Ohio, have invented certain new and useful Improvements in Ratchet-Drills; and I do hereby declare the following to be a full, clear, and exact description thereof, reference being had to the accompanying drawings, which form a part of this specification.

My invention relates to an improved ratchet-drill; and it consists in the provision of a device whereby the drill while being operated may be fed forward, together with the certain details of construction and combination of parts, as will be fully described hereinafter.

In the accompanying drawings, Figure 1 is a side elevation of my improved ratchet-drill, which is constructed and arranged in accordance with my invention. Fig. 2 is an end elevation of the same, a part of which is shown in section. Fig. 3 is a sectional side elevation of the lower portion of the drill. Fig. 4 is an end elevation of the lower portion of the drill, showing the side opposite to that of Fig. 2. Fig. 5 is a perspective view of the pin upon which the several pawls operate. Fig. 6 is a perspective view of the short lever attached to the pin above described. Fig. 7 is a side elevation of the adjusting-screw detached from its position.

To construct a ratchet-drill in accordance with my invention, I provide a lever 1 of a suitable length and form at the base of the same a transverse cylindrical opening for the reception of the socket portion 2. This socket portion is formed with a ratchet-wheel 5 and is held in position by a second ratchet-wheel 4, located upon the opposite side of the handle 1, and the two pieces 2 and 4 joined the one to the other by screws 6 in a manner that will permit the parts to freely revolve in the handle. Placed through the handle 1 a short distance above the socket-piece 2 is a pin 18, upon which two pawls 14 and 16 are journaled, one on either side of the handle, to engage with the ratchet-wheels 4 and 5 and the said pawls provided with springs 15 to keep the same engaged with the teeth of the ratchets. Journalled to the ratchet-wheel 4, by means of a threaded pin 9, is a shank 8, formed with a ratchet 13 and provided with an intermediate ball-bearing 7 and at its rear with a threaded socket 10, in which a threaded pin 11 is made to operate, the said pin be-

ing provided with a barbed head 12. Rigidly attached to the one end of the pin 18 above described is a pawl 17, adapted to engage with the last-mentioned ratchet 13, and attached to the said pin is a short lever 19, which extends radially therefrom. This short lever 19 is located in a cavity formed in the handle, and a spiral spring is placed beneath the lever to keep the pawl 17 disengaged from its ratchet. Placed in an opening formed lengthwise of the handle 1 is a rod 20, adapted to engage with the short lever 19, and the said lever projecting slightly beyond the end of the handle and held in position by a transverse pin operating through a slot formed in the rod.

In operation the ratchet-drill above described is arranged in a position and is operated in the same manner as those now in common use, except when it is desired to feed the drill forward, which is accomplished by pressing the rod downward, thereby slightly rotating the pin 18 and engaging the pawl 17 with its ratchet 13, and by a movement of the handle the shank is turned and fed forward by the action of the screw 11.

Various slight modifications and changes may be made in the details of construction without departing from the spirit of the invention.

Having thus described my invention, what I claim, and desire to secure by Letters Patent, is—

The herein-described ratchet-drill, consisting of the handle, 1, the socket portion 2 loosely mounted therein, the two ratchet-wheels 4, and 5, one on either side of the handle, the pawls 14, and 16 for engaging the said ratchet-wheels, the threaded shank 8, having a ratchet 13, the pawl 17, mounted upon the pin 18, the said pin being provided with a short lever 19 backed by a suitable spring, the rod 20 arranged within the handle for operating the lever, and a means for confining the said rod in position, all arranged and combined for service substantially as and for the purpose described.

In testimony whereof I have hereunto affixed my signature in the presence of two subscribing witnesses.

JOHN PETTERSON.
